UNITED STATES PATENT OFFICE.

JOSEPH W. KYLE, OF CHICAGO, ILLINOIS.

OIL-CUP.

No. 878,808.

Specification of Letters Patent.

Patented Feb. 11, 1908.

Application filed April 20, 1907. Serial No. 369,233.

To all whom it may concern:

Be it known that I, JOSEPH W. KYLE, a citizen of the United States, and a resident of the city of Chicago, county of Cook, and

5 State of Illinois, have invented certain new and useful Improvements in Oil-Cups; and I do hereby declare that the following is a full, clear, and exact description of the same, reference being had to the accompanying drawings, and to the letters of reference marked thereon, which form a part of this specification.

This invention relates to improvements in oil cups of the class set forth in the prior 15 application of John B. Reimund and myself, filed May 7, 1906, Serial No. 315,682.

Heretofore oil cups of this class have been somewhat uncertain in feeding the oil and have often proven unsatisfactory inasmuch 20 as the cups, though feeding the desired amount when full, or nearly full, sometimes feed more slowly as the quantity of oil in the cup decreases, thereby providing insufficient lubrication. Such cups frequently will not 25 feed all of the oil to the journal to be lubricated, for when the cups are only partly filled the oil instead of passing into the feed tube is deflected past the same or into the bottom of the cup and an insufficient amount 30 passes into the tube. Furthermore oil cups that are removable from a fixed nipple which covers and closes an air displacement aperture, when an imperfect fit or when the attaching means are slightly worn, permit 35 centrifugal force to throw the cup slightly away from the nipple thus admitting sufficient air into the oil cup to cause an imperfect feed of the oil.

It is an object of this invention to provide 40 connecting means for the cup and nipple which yieldingly but positively and detachably secure the same in proper relation without the necessity of accurate machining and which insures a perfect fit, independently of 45 the wear of the parts, or any possible working conditions.

It is a further object of this invention to provide means for feeding the oil to the journal at a uniform rate, independently 50 of the amount in the cup and until the cup is empty.

It is also an object of this invention to

provide an efficient, positively operating device of few parts and which can be quickly and easily detached, filled and replaced and 55 from which the oil will not spill.

The invention consists in the matters hereinafter described and more fully pointed out and defined in the appended claims.

On the drawings: Figure 1 is a side elevation of a loose pulley provided with devices embodying my invention. Fig. 2 is an enlarged side elevation of a device embodying my invention. Fig. 3 is a section taken on line 3—3 of Fig. 2. Fig. 4 is an enlarged 60 side elevation of the nipple. Fig. 5 is a top plan view of the connecting means. Fig. 6 is an enlarged transverse section of the deflector.

In the drawings: A indicates an oil cup of 70 any desired shape but which is shown as cylindrical and is provided with an integral conical top. A bottom plate a, provided with a peripheral upturned flange a', fits within the cup and is brazed, or otherwise secured in the 75 cup. A central circular aperture surrounded by an upturned flange is provided in said bottom, through which extends the feed pipe or tube B, which is secured therein, in any preferred manner to afford a tight joint. Said 80 tube extends into the cup to near the top and outwardly beyond the bottom any desired distance.

Centrally secured at its base to the top of 85 said cup A is a deflector C, which as shown, is pyramidal in form having four concave sides, and the apex of which is directed axially into the upper end of said tube, to any desired distance.

A nipple D having an externally screw 90 threaded lower end d for engagement to the hub of the loose pulley or other revolving element in the journal to be lubricated, is axially bored for its entire length and the outer end of said bore is enlarged to receive 95 the outwardly extending end of the feed tube B therein. The outer end of said nipple is flattened to fit closely against the bottom a, and to seal the vent apertures a² therein, when the cup is secured in place. The attaching means comprises a ring E which is brazed, threaded, shrunk or otherwise rigidly secured to the nipple D, and is provided on opposite sides thereof with resilient spring 100

arms $e-e'$, adapted to engage in the oppositely disposed slots e^2 , similar to bayonet joint notches, in the sides of the cup below the bottom plate a . A slight swell or shoulder e^3 , 5 is provided in each notch over which the resilient arms $e-e'$ are sprung when the cup is engaged on the nipple.

The operation is as follows: The cup is filled through the tube B, and the vent aperture or apertures a^2 allows the air in the cup to escape as the cup fills. The cup and nipple are quickly attached by inserting the resilient arms in said slots e^2 , and slightly turning the cup, the resilient arms spring over the 15 shoulders and lock the cup from removal except when considerable force is applied. When secured together the nipple closes the vent aperture a^2 , and prevents the loss of the lubricant therethrough and prevents ingress of air. Furthermore owing to the resilient arms $e-e'$, a pressure is always exerted on the cup oppositely to centrifugal force, to hold the bottom a tightly against the top of the nipple, thereby at all times closing the 20 vent aperture. Owing to the deflector C, a part of the oil thrown outwardly by centrifugal force instead passing the top of the tube B, is intercepted by said concave deflector and during each revolution, as the cup assumes an upright position a small portion of the oil is delivered from said deflector to the feed tube and thence through the nipple to the journal. Obviously if desired more than 25 two resilient locking arms may be provided 30 and the deflector may be of any preferred kind or form and the sides of the deflector may be differently shaped. I therefore do not purpose limiting this application otherwise than necessitated by the prior art.

40 I claim as my invention:

1. In a device of the class described the combination with a rotatable member of an oil cup, a nipple adapted for connection with the rotatable member, resilient means adapted to detachably connect said cup and nipple, said means acting oppositely from centrifugal force.

2. In a device of the class described the combination with a loose pulley oil cup, of a 50 nipple threaded for engagement with the part to be lubricated, and resilient locking arms adapted to detachably secure said cup and nipple together.

3. A centrifugally acting oil cup having a 55 permanent bottom therein, a tube extending therethrough, means adapted to deflect the oil into said tube, detachable means engaging said cup to the object to be lubricated and resilient connections between the same and oil cup.

4. In a device of the class described the combination with an oil cup of a closed bottom therein having a vent aperture therethrough, a feed tube extending through said

bottom, a deflector engaged in the top of the 65 cup and extending into said feed tube, a nipple cored to receive the outer end of said tube and adapted to abut against said bottom to close the air vent and resilient means acting against centrifugal force and adapted 70 to detachably secure said cup on said nipple.

5. An oil cup wholly closed except for a vent aperture in its bottom for the displacement of air in filling and a filling and feed tube connected through the bottom, a deflector in said cup, a nipple bored to conduct the oil from said tube to the journal and adapted to engage the cup to the object lubricated and normally to close the air vent and resilient means on said nipple to detachably engage said cup thereto.

6. In a device of the class described the combination with an oil cup of a feed and filling tube extending thereto and therefrom, means adapted to deflect the oil into 85 the inner end of said tube, means adapted to receive the end of said tube and to be engaged to the object to be lubricated and resilient arms adapted to detachably engage the same and said cup together.

7. In a loose pulley oil cup deflector adapted to guide the oil to the discharge aperture, means adapted to connect the cup to the lubricated object and resilient means detachably engaging the same and cup together and 95 acting against centrifugal force.

8. In a device of the class described the combination with an oil cup having a permanent bottom thereon provided with an aperture, a feed and filling tube extending 100 through the partition to near the top of the cup, a deflector rigidly engaged to the cup adapted to supply oil to the tube, a nipple adapted to receive the end of said tube and having a passage therethrough and resilient 105 arms carried by the nipple adapted to engage in slots in the cup to detachably engage said nipple to the cup.

9. An oil cup having a bottom provided with an air vent therethrough, a nipple cored to permit the oil passing to the object lubricated and resilient means securing the nipple to the cup adapted to force the bottom of the cup against the nipple to prevent ingress of air through the air vent when in operation.

10. An oil cup, a nipple having a passage therethrough and resilient means detachably securing the cup to the nipple.

11. An oil cup having notches on opposite sides thereof and provided with shoulders, a nipple having a threaded lower end and a central passage to permit oil passing therethrough and oppositely disposed arms on said nipple adapted to be sprung over the shoulders in attaching and detaching the cup to the nipple.

12. An oil cup having a bottom therein, a

feed tube extending through the bottom, said bottom having an aperture for air displacement in filling, a nipple adapted to be rigidly engaged to the object to be lubricated and resilient arms detachably securing the cup to the nipple.

5 In testimony whereof I have hereunto sub-

scribed my name in the presence of two subscribing witnesses.
